UNITED STATES PATENT OFFICE.

MICHAEL KOTT, OF NEW YORK, N. Y.

CURTAIN STRETCHER.

Application filed March 11, 1926. Serial No. 93,998.

This invention relates to a curtain stretcher.

An object of the invention is to provide a curtain stretcher which avoids the necessity of using pins in the frame of the stretcher gripping the curtain.

A further object is to provide a curtain stretcher which will grip the curtain firmly along its edges and stretch it evenly.

10 A further object is to provide a suitable frame which can be very quickly and easily fastened to the curtain and removed therefrom when desired.

15 A still further object is to provide a frame which can be readily disassembled and folded away in a small, compact unit.

The invention is illustrated in the drawings, of which—

20 Figure 1 is a plan view of the stretcher shown applied to a curtain.

Figure 2 is a section on the line 2—2 of Figure 1;

Figure 3 is a section on the line 3—3 of Figure 1;

25 Figure 4 is a section on the line 4—4 of Figure 1;

Figure 5 is a section on the line 5—5 of Figure 1;

30 Figure 6 is a section on the line 6—6 of Figure 1.

Figure 7 is a section on the line 7—7 of Figure 1.

The form of the invention shown in the drawings is a preferred form, although it is understood that modifications in the construction and arrangement of the parts and in the character of the material used may be adopted without departing from the spirit of the invention as set forth in the appended claim.

40 In its general aspect the invention includes a frame comprising side and end members, each of which is foldable so that when folded and put away it will occupy a much smaller space than when operatively assembled. Each of the members comprises a pair of hinged sections, preferably hinged along their outside longitudinal edges and adapted to grip the edges of the curtains between them. They are preferably held in this gripping relation by suitable removable clamps. The foldable sections can be held in their operative positions by means of latch members which, when they are withdrawn, will permit the sections to be folded.

Preferably the side sections are foldable in one plane at right angles to the plane in which the curtain lies when it is stretched, whereas the end sections are foldable in the same plane with the plane of the curtain.

45 In applying the device the side sections are extended and latched in this position and then the pivoted portions are separated sufficiently far to insert therebetween the side edges of the curtain, after which the sections are clamped on to the curtain by means of the removable clamps. The end sections of the curtain are then attached to the end edges of the curtain and before these sections have been fully stretched to their ultimate position after the curtain has been properly clamped between the end sections, each are fastened to the opposite ends of the side sections and are then moved to their fully extended position during which movement the curtain is properly stretched.

50 In the preferred form of the invention shown in the drawings, I provide two side sections which are foldable, each of the side sections comprising longitudinally disposed strips 10 and 11, hinged at their outside longitudinal edges by hinges such as 12 and 13. These strips are split as at 14 and are bendable so as to be folded together when not in use. A hinge 15 is provided along these split portions to permit them to be folded. The top of one strip adjacent the joint or split is provided with a plate 16 which extends over the top of the adjoining section across the joint. This plate being provided with an aperture 17 through which a metallic eye 18 extends. This eye receives a pin 19 which holds the portions of the side sections in their extended position.

55 Preferably along one end on each side section it is provided with a series of holes 20 extending through both the upper and lower strips. These holes are for the purpose of permitting the end sections to be fixed temporarily to the side sections at the required distance apart, in accordance with the size of the curtain being stretched.

60 When the curtain is to be stretched it is clamped between the hinged strips 10 and 11 of the side sections as shown in Figure 3, the curtain being represented by the numeral 21. The fact that the upper and lower strips are hinged together will permit them to be separated so that the curtain can be inserted therebetween. The strips are held clamped on the curtain by means of spring

plates 22 and 23, the front ends of which engage the upper and lower strips, the rear ends of which are adjustably separated by an adjusting screw 24. The strips are pivoted to a spacer member 25 held between the plates preferably by a bolt 26. If desired these clamping members can be removable from the sections or as shown in Figure 5 they can be fastened permanently thereto. 10 by any suitable means such as bolts 27 which connect the lower plate 23 permanently to the lower strip 11 of the section. In order to unclamp the sections the screw 24 is loosened and then the upper plate can be swung sideways with respect to the lower plate to permit the upper section 10 to be moved to the dot and dash position shown in Figure 5 so that the curtain can be withdrawn. It will be noticed that the latching arrangement 20 shown in Figure 2 when released or unlatched will permit the side section to be moved or folded in a plane at right angles to the plane of the curtain when stretched. Therefore, when attaching the frame to the 25 curtain the side elements of the frame are moved to their extended position and latched in this position, after which the upper and lower strips are separated to permit of the insertion therebetween of the edge of the 30 curtain. The strips are then clamped on the curtain as described.

The ends of the curtain are fastened for which purpose end bar sections are provided. These end bar sections each comprise upper 35 and lower sections 28, 29, 30 and 31, hinged along their rear edges as at 32 to permit them to be separated to receive the edge of the curtain. The sections are hinged to a plate 33 for longitudinal movement in the plane of the curtain, this plate extending across between the adjacent edges of the portions of the end sections. On opposite sides of the join between these portions are disposed keepers 34 and 35 which, when alined 40 as shown in Figures 1 and 6, will receive a latch bar 36 so that they will be held in their extended position.

In order to apply the end sections of the 50 curtain the end sections are at their opposite ends each fastened to the side sections of the frame by means of bolts 37 having wing nuts 38 on the bottom. These bolts extend through openings in the bottom strips of the end sections and in the top and bot-

tom strips of the side sections. In other 55 words these bolts pass through the holes 20 above mentioned. The holes into which these bolts are disposed are determined in accordance with where the end of the curtain comes on the side sections. 60

After the end sections are thus fastened with respect to the side sections, the top and bottom strips of the end sections are opened to receive the ends of the curtain. This is done before the end sections are extended and while they are in the dot and dash position shown in Figure 1. After the curtain has been received between the top and bottom strips of the end sections these strips are then clamped together as above 70 mentioned and are moved to their extended position as shown in full line in Figure 1. When this takes place the sliding bar 36 is moved into position to hold the end sections. 75

It will be observed that this frame requires no pins which pass through the edges of the curtain. It is also observed that the frame can be folded up into a comparatively small size when not in use. It is also 80 to be observed that when applying the end sections of the curtain and moving them to their operative positions the curtain becomes fully stretched.

What I claim is:

A curtain stretcher frame including upper and lower side strips between which the curtain may be clamped, hinges connecting said upper and lower strips and clamps provided on said strips for holding the same in clamping relation to the curtain, said clamps each comprising the following instrumentalities: a clamp plate secured at one end to one of said strips and extending transversely therefrom, a second plate adapted at one end to overlie the other of said strips, a screw extending through the other end of the second mentioned plate and bearing against the first mentioned plate to effect a clamping action on the strips, a transverse pivot pin extending through both plates intermediate their ends and a spacing member between the plates intermediate their ends and through which said pin also extends, the upper plate being adapted to turn on said pin when said screw is loosened. 100 90 95 105
